(57) **CLAIM**

We claim the ornamental design for a closure with integrated dosage cup, as shown and described.

DESCRIPTION

FIG. 1 is a top perspective view of the claimed design; FIG. 2 is a first elevation view of the claimed design of FIG. 1;

FIG. 3 is a second elevation view of the claimed design of FIG. 1;

FIG. 4 is a top plan view of the claimed design of FIG. 1; FIG. 5 is a bottom plan view of the claimed design of FIG. 1; and,

FIG. 6 is a cross sectional view of the claimed design of FIG. 1 taken along a line 6-6 in FIG. 4.

The ornamental design which is claimed is shown in solid lines in the drawings. The broken lines in the drawings depict portions of the closure with integrated dosage cup that form no part of the claimed design. The areas between the representative break lines form no part of the claimed design.
